UNITED STATES PATENT OFFICE.

JOSEPH L. CATO, OF ELMHURST, NEW YORK.

EXPLOSION ENGINE.

Application filed September 24, 1919. Serial No. 326,191.

To all whom it may concern:

Be it known that I, JOSEPH L. CATO, a citizen of the United States, residing at Elmhurst, in the county of Queens and State of New York, have invented a certain new and useful Improvement in Explosion Engines, of which the following is a specification.

My invention is applicable to internal 10 combustion engines of many different kinds, but is especially applicable to such engines used for driving automobiles or aeroplanes.

The object of my invention is to provide an internal combustion engine having an 15 effective cooling means, which is of such character that an engine provided with said cooling means will have less weight than the engines using previously-known cooling systems.

20 A further object is to provide internal combustion engines with effective air cooling systems.

Still another object of my invention is to provide an engine of this kind having a 25 current of air continually applied to the interior of the cylinder in an effective manner, owing to the presence of a stationary piston cooperating with the movable piston of the engine.

30 Further objects of my invention will appear from the detailed description thereof contained hereinafter.

While my invention is capable of embodiment in many different forms, for the 35 purpose of illustration I have shown only one form of the same in the accompanying drawings, in which:

Figure 1 is a cross-section of a portion of an engine cylinder and piston made in 40 accordance with my invention;

Figure 2 is a bottom view of said piston;

Figure 3 is a transverse section of said piston; and

Figure 4 is another transverse section of 45 the same taken on line 4-4 of Figure 3.

In the drawings, I have shown a cylinder 1 of an aeroplane engine of internal combustion type, having at the top thereof a closure 2, provided with a spark plug 3 at one side thereof, an inlet port 4 for a fuel mixture, controlled by a valve 5, and an outlet port 6 for the products of combustion, controlled by a valve 7. In the cylinder 1, there is provided a port 55 8 for the passage of air, which at all times communicates with a longitudinal passage-

way 9 on one side of a piston 10, the lower end of which passageway 9 is closed by a flange 11, but the upper end of which is open to communicate with a plurality of 60 transverse passageways 12, formed by a transverse strengthening partition 13. In the passageways 12 there are a plurality of transverse fins 14, to increase the cooling effect of the air. On the side of the 65 piston 10 opposite to the location of the passageway 9, there is a further passageway 15, which is open at the top, but the lower end of which is closed by a stationary piston 16, carried by the lower end of the cylinder 1, and held in place by a plurality of screws 17, passing from the cylinder 1 into a crank casing 18. It will also be noted that the passageways 9 and 15 are connected by a hollow crank pin 19, held in place 70 in the piston 10 by a screw 20, and which supports a connecting rod 21. Additional cooling is secured in this way. If desired, a still greater cooling effect may be obtained by providing fins 22 on the outside of the 75 cylinder 1.

In the operation of my invention, as the piston 10 reciprocates, currents of air are first drawn in through the port 8 upon the upward stroke of said piston, and are forced out through the port 8 upon the downward stroke of said piston, owing to the presence of the stationary piston 16. These currents of air pass not only over much of the interior of the piston 10, but come into 85 contact with the cooling fins 14, as well as the interior of the crank pin 19, so that the cylinder 1 is effectively cooled from the inside by these currents of air. A further cooling effect is secured by the presence 90 of the fins 22 on the outside of the cylinder 1.

While I have described my invention above in detail, I wish it to be understood that many changes may be made therein 100 without departing from the spirit of the same.

I claim:

1. An internal combustion engine having in a cylinder means for providing therein 105 a current of air, comprising a stationary partition cooperating with an engine piston and fitting in a passageway located at one side of the piston.

2. An internal combustion engine having 110 in a cylinder means for providing therein a current of air, comprising a stationary par-

- 2
- 5 tition cooperating with an engine piston and fitting in a passageway located at one side of the piston and a continuously open port in the cylinder.
- 10 5. An internal combustion engine having in a cylinder means for providing therein a current of air, comprising a stationary partition cooperating with an engine piston and fitting in a passageway located at one side of the piston and a continuously open port in the cylinder cooperating with a passageway in the piston.
- 15 6. An internal combustion engine having in a cylinder means for providing therein a current of air, comprising a stationary partition cooperating with an engine piston and a fin extending transversely through the piston in contact with said current of air.
- 20 7. An internal combustion engine having in a cylinder means for providing therein a current of air, comprising a stationary partition cooperating with an engine piston and fitting in a passageway located at one side of the piston and a fin extending transversely through the piston in contact with said current of air.
- 25 8. An internal combustion engine having in a cylinder means for providing therein a current of air, comprising a stationary partition cooperating with an engine piston, a continuously open port in the cylinder, and a fin extending transversely through the piston in contact with said current of air.
- 30 9. An internal combustion engine having in a cylinder means for providing therein a current of air, comprising a stationary partition cooperating with an engine piston and fitting in a passageway located at one side of the piston, a continuously open port in the cylinder, and a fin extending transversely through the piston in contact with said current of air.
- 35 10. An internal combustion engine having in a cylinder means for providing therein a current of air, comprising a stationary partition cooperating with an engine piston and fitting in a passageway located at one side of the piston, a continuously open port in the cylinder, and a fin extending transversely through the piston in contact with said current of air.
- 40 11. An internal combustion engine having in a cylinder means for providing therein a current of air, comprising a stationary partition cooperating with an engine piston and fitting in a passageway located at one side of the piston, a continuously open port in the cylinder, and a fin extending transversely through the piston in contact with said current of air.
- 45 12. An internal combustion engine having in a cylinder means for providing therein a current of air, comprising a stationary partition cooperating with an engine piston and fitting in a passageway located at one side of the piston, a continuously open port in the cylinder, and a fin extending transversely through the piston in contact with said current of air.
- 50 13. An internal combustion engine having in a cylinder means for providing therein a current of air, comprising a stationary partition cooperating with an engine piston and fitting in a passageway located at one side of the piston, a continuously open port in the cylinder, and a fin extending transversely through the piston in contact with said current of air.
- 55 14. An internal combustion engine having in a cylinder means for providing therein a current of air, comprising a stationary partition cooperating with an engine piston and fitting in a passageway located at one side of the piston, a continuously open port in the cylinder, and a fin extending transversely through the piston in contact with said current of air.
- 60 15. An internal combustion engine having in a cylinder means for providing therein a current of air, comprising longitudinal and transverse passageways in the piston, a port in the cylinder leading to a longitudinal passageway, and a stationary partition near said port.
- 65 16. An internal combustion engine having in a cylinder means for providing therein a current of air, comprising longitudinal and transverse passageways in the piston, said transverse passageway having a cooling fin therein, a port in the cylinder leading to a longitudinal passageway, and a stationary partition near said port.
- 70 17. An internal combustion engine having in a cylinder means for providing therein a current of air, comprising longitudinal and transverse passageways in the piston, said transverse passageway having a cooling fin therein, a port in the cylinder leading to a longitudinal passageway, and a stationary partition near said port.
- 75 18. An internal combustion engine having in a cylinder means for providing therein a current of air, comprising longitudinal and transverse passageways in the piston, said transverse passageway having a cooling fin therein, a port in the cylinder leading to a longitudinal passageway, and a stationary partition near said port.
- 80 19. An internal combustion engine having in a cylinder means for providing therein a current of air, comprising longitudinal and transverse passageways in the piston, and a crank pin passageway also connecting the longitudinal passageways.
- 85 20. An internal combustion engine having in a cylinder means for providing therein a current of air, comprising longitudinal and transverse passageways in the piston, said transverse passageway having a cooling fin therein, and a crank pin passageway also connecting the longitudinal passageways.
- 90 21. An internal combustion engine having in a cylinder means for providing therein a current of air, comprising longitudinal passageways in the piston and a crank pin passageway connecting the same.
- 95 In testimony that I claim the foregoing, I have hereunto set my hand this 22nd day of September, 1919.

JOSEPH L. CATO.
